[57] **CLAIM**

The ornamental design for a magnetic soap holder, as shown and described.

DESCRIPTION

FIG. 1 is a perspective view of a magnetic soap holder without the insert showing my new design;

FIG. 2 is an environmental perspective view of a magnetic soap holder with the insert and a bar of soap;

FIG. 3 is a front elevational view thereof;

FIG. 4 is a top view thereof;

FIG. 5 is a right side elevational view with the left side being a mirror image thereof; and,

FIG. 6 is a bottom view thereof.

The broken line showing of the bar of soap is for illustrative purposes only and forms no part of the claimed design. The rear view of the invention, not shown, is plain and unornamented.
